TRAY FOR A WRAPPED FRUIT CONTAINER

Joseph E. Murphy, Hicksville, and Murray Schnall, Brooklyn, N. Y., assignors to See-Qual Package Corp., New York, N. Y., a corporation of New York

Application March 11, 1954, Serial No. 29,468

Term of patent 14 years

(Cl. D58—26)

FIG. 2.

FIG. 1.

FIG. 3.

FIG. 4.

FIG. 5.

FIG. 6.

We claim:

The ornamental design for a tray for a wrapped fruit container, substantially as shown.
